BOUQUET HOLDER

Olga Louise Wurzlow, Houma, La.

Application January 8, 1951, Serial No. 13,712

Term of patent 14 years

(Cl. D29—28)

To all whom it may concern:

Be it known that I, Olga Louise Wurzlow, a citizen of the United States of America, residing at Houma, in the county of Terrebonne and State of Louisiana, have invented a new, original, and ornamental Design for Bouquet Holder, of which the following is a specification, reference being had to the accompanying drawing, forming a part thereof, wherein:

Fig. 1 is a side elevation view of a bouquet holder, showing my new design; and

Fig. 2 is a view similar to that shown in Fig. 1 with article rotated at 60 degrees;

Fig. 3 is a top plan view.

I claim:

The ornamental design for a bouquet holder, as shown.

OLGA LOUISE WURZLOW.
